MULTIPLE TEMPERATURE REFRIGERATION

Morris F. Booth, Alden, Mich.

Application June 10, 1946, Serial No. 675,601

9 Claims. (Cl. 62—116)

1

This invention relates to multiple temperature refrigeration and is more particularly concerned with a system providing both a frozen food storage compartment and a normal refrigerated compartment wherein an improved system and control are incorporated.

It is an object of the present invention to provide a system of this character wherein the low temperature compartment is cooled by a refrigerant evaporator connected in the usual refrigerating circuit, which evaporator has means for circulating a secondary heat transfer liquid which in turn is led through the normal refrigerated food compartment having a heat exchanger therein. In systems of this character, the heat loads upon the two compartments may vary independently of one another and the refrigeration demand at one has no coordination with the demand at the other. Thus it may happen that both compartments demand refrigeration at about the same time and due to the temperature difference between them the circulation of heat transfer fluid tends to prevent the evaporator from properly bringing down the temperature in the low temperature compartment. This is particularly true where the heat transfer fluid and the refrigerant in the evaporator are in close relation for good heat transfer. Unless the evaporator is connected to a very powerful high side, it frequently occurs that the demands of the high temperature compartment prevent the low temperature compartment from pulling down and in fact may tend to raise its temperature under these conditions.

It is also an object of the present invention, therefore, to provide a control system which enables a small size high side to take care of the demand of both compartments and at the same time to prevent the low temperature compartment from ever getting above its predetermined desired temperature.

Figure 1 is a diagrammatic view of a refrigerating system incorporating a preferred form of the present invention.

Figure 2 is a fragmentary cross section of an evaporator incorporated in the device of Figure 1.

In the system illustrated, 10 represents a low temperature compartment such as may be used for frozen food storage or food freezing and wherein the temperatures of the order of 0° F. may be maintained; 12 represents a normally refrigerated storage compartment wherein temperatures of the order of 40° F. are maintained. The compartment 10 is cooled by an evaporator

2

14 connected to the usual high side 16 in a conventional refrigeration circuit 18.

The evaporator 14 is preferably formed of extruded metal having a cross section as illustrated at Figure 2. It will be seen that the extrusion is rectangular in cross sectional outline and has two parallel passages 20 and 22 extending continuously there-through. The passage 20 may form the evaporator and carry the refrigerant flowing through the high side 16. The passage 22 being in intimate heat exchange relation with the passage 20 is adapted to be connected in a circuit carrying brine or other low temperature heat transfer fluid. This circuit comprising the conduits 24, 26 and 28 has a circulating pump 30 therein and also a heat exchanger 32 positioned in the compartment 12. The heat exchanger 32 may have provision for the usual ice trays 34. The pump 30 may be driven by an electric motor 36 which is supplied from a power line 38 through conductors 40. The motor is under the control of thermostatic switches 42 and 44 located in the compartments 10 and 12, respectively. The thermostat 42 is of the type which closes when the temperature falls while the thermostat 44 is of the type which closes when the temperature rises. The circuit for the motor 36 is so arranged that both thermostats are in series with the motor which can only operate when both thermostats are closed.

In operation the high side 16, which is of course provided with the usual thermostatic controls not illustrated, acts to maintain the temperature within compartment 10 between predetermined limits, for example, minus 5 to plus 10° F. The switch 42 may be set to close at zero and to open at plus 5, while the switch 44 may be set to close at 30 and open at 25 assuming it to be mounted on the heat exchanger 32. Thus when the evaporator 14 pulls down to a temperature of zero, the heat transfer circuit is then made available for cooling the compartment 12 if such be necessary. As soon thereafter as the switch 44 closes by the temperature of heat exchanger 32 reaching 30°, the circuit to motor 36 will be completed and pump 30 will operate to cause circulation of fluid through the conduits 24, 26 and 28 thus absorbing heat from the compartment 12 by the heat exchanger 32 and transferring it to the fluid in the evaporator coil 14. As soon as the heat exchanger 32 pulls down to 25°, switch 44 opens, stopping this circulation. If it should happen that the heat transferred to evaporator 14 were sufficient to raise the temperature in compartment 10 above 5° F., switch 42 would open thus

stopping the circulation of heat transfer fluid until the high side 16 has an opportunity to again pull the compartment 10 down to zero.

While the system thus far described shows only two compartments to be refrigerated, it may be used for as many additional compartments as desired and one way of so utilizing this system is indicated at the compartment 46. This may be a portable unit such as an ice cream freezer having a heat exchanger 48 for handling the heat transfer fluid and having a thermostatic switch 50 similar to the switch 44. The switch 50 is adapted to be connected in parallel with the switch 44 by conductors 52 having a separable plug and socket 54 therein. The conduit 28 is provided with two T branches 56 between which is connected a thermostatic snap acting valve 59 responsive to the temperature in compartment 12. The heat exchanger 48 may be connected to the branches 56 by separable self-closing couplings 58 of the conventional type which operate to seal their open ends when the couplings are disconnected thus retaining the fluid in the circuit. The operation of this portion of the circuit will be similar to that previously described.

The valve 59 may be set to open and close at the same temperatures for which the switch 44 is set so that whenever compartment 12 is demanding refrigeration, the heat exchanger 48 is bypassed through the valve 59. Whenever the refrigerated demand of compartment 12 is satisfied, valve 59 closes and the pump 36 may then be operated under the control of switch 50. Thus even though switch 44 be open, switch 50 may start or maintain the motor 36 in operation subject only to the supervisory control of the switch 42.

Should it happen that the portable compartment 46 be plugged into the circuit at a time while compartment 12 is warming up and the temperature is at an intermediate point between 25 and 30°, the thermostat 50 when it is plugged in at 54 will start the pump 30 in operation. However, valve 59 will be closed at this time so that the heat transfer fluid will have to pass through the heat exchanger 48 before going to the evaporator 14. This will have the effect of cooling both the compartments 12 and 46. If overcooling of compartment 12 is objectionable in a given installation, a suitable thermostatically controlled by-pass around the heat exchanger 32 may be provided.

I claim:

1. In a two-temperature refrigeration system the combination of a low temperature evaporator in heat exchange relation to a compartment to be cooled, means forming a path for a heat exchange liquid through said evaporator but isolated from the refrigerant therein, a heat exchanger in thermal relation to a second compartment to be cooled to a higher temperature, a secondary fluid circuit comprising the heat exchanger, said means, and connecting conduits, electrically operated means for controlling flow in the secondary circuit, electric means operatively associated with said electrically operated means to govern the same, and two thermostats in series with each other and with said electric means one responsive to evaporator temperature and the other responsive to heat exchanger temperature for governing said electric means to prevent fluid flow in the secondary circuit except when the evaporator is below a predetermined temperature and the heat exchanger is above a higher predetermined temperature.

2. In a two-temperature refrigeration system the combination of a low temperature evaporator in heat exchange relation to a compartment to be cooled, means forming a path for refrigerant and a heat exchange liquid through said evaporator, each path being isolated from the other, comprising a pair of adjacent coiled conduits with alternate passages for refrigerant and heat exchange fluid, a heat exchanger in thermal relation to a second compartment to be cooled to a higher temperature, a secondary fluid circuit for heat exchange fluid comprising the heat exchanger, one path of said means, and connecting conduits, electrically operated means for controlling the flow in said circuit, electric means for governing said electrically operated means, and two thermostats in series with each other and with said electric means one responsive to evaporator temperature and the other responsive to heat exchanger temperature for governing said electric means to prevent fluid flow in the secondary circuit except when the evaporator is below a predetermined temperature and the heat exchanger is above a higher predetermined temperature.

3. In a two-temperature refrigeration system the combination of a low temperature evaporator in heat exchange relation to a compartment to be cooled, means forming a path for a refrigerant and a heat exchange liquid through said evaporator, each path being isolated from the other, comprising a pair of adjacent coiled conduits with alternate passages for refrigerant and heat exchange fluid formed in a homogeneous extruded metal bar, a heat exchanger in thermal relation to a second compartment to be cooled to a higher temperature, connecting conduits between said heat exchanger and said means, a secondary fluid circuit comprising the heat exchanger and one path of said means with connecting conduits, means for controlling flow in the secondary circuit and two thermostats, one responsive to evaporator temperature and the other responsive to heat exchanger temperature, for governing said last named means to prevent fluid flow in the secondary circuit except when the evaporator is below a predetermined temperature and the heat exchanger is above a higher predetermined temperature.

4. In a two-temperature refrigeration system the combination of a low temperature evaporator in heat exchange relation to a compartment to be cooled, means forming a path for a heat exchange liquid through said evaporator but isolated from the refrigerant therein, a heat exchanger in thermal relation to a second compartment to be cooled to a higher temperature, a secondary fluid circuit comprising the heat exchanger, said means, and connecting conduits, fluid control means for causing movement of fluid through the secondary circuit, thermostatic means responsive to conditions at the higher temperature compartment for governing said fluid control means and a second thermostatic means in series with said first thermostatic means responsive to temperature at the evaporator governing said fluid control means to prevent initiation of flow except when the evaporator is below a predetermined temperature.

5. In a two-temperature refrigeration system the combination of a low temperature evaporator in heat exchange relation to a compartment to be cooled, means forming a path for a heat exchange liquid through said evaporator but isolated from the refrigerant therein, a heat ex-

changer in thermal relation to a second compartment to be cooled to a higher temperature, a secondary fluid circuit comprising the heat exchanger, said means, and connecting conduits, fluid control means for causing fluid flow through the secondary circuit, means responsive to a predetermined rise in temperature at the high temperature compartment and means responsive to a predetermined low temperature at the evaporator for conjointly governing said fluid control means.

6. In a two-temperature refrigeration system the combination of a low temperature evaporator in heat exchange relation to a compartment to be cooled, means forming a path for a heat exchange liquid through said evaporator but isolated from the refrigerant therein, a heat exchanger in thermal relation to a second compartment to be cooled to a higher temperature, a secondary fluid circuit comprising the heat exchanger, said means, and connecting conduits, an electrically driven pump for causing fluid flow through the secondary circuit, thermostatic means responsive to conditions at the higher temperature compartment for controlling said pump and a second thermostatic means responsive to temperature at the evaporator for preventing initiation of flow by said pump except when the evaporator is below a predetermined temperature.

7. In a two-temperature refrigeration system the combination of a low temperature evaporator in heat exchange relation to a compartment to be cooled, means forming a path for a heat exchange liquid through said evaporator but isolated from the refrigerant therein, a heat exchanger in thermal relation to a second compartment to be cooled to a higher temperature, a secondary fluid circuit comprising the heat exchanger, said means, and connecting conduits, an electrically driven pump for causing fluid flow through the secondary circuit, means responsive to a predetermined rise in temperature at the high temperature compartment and means responsive to a predetermined low temperature at the evaporator for conjointly controlling said pump.

8. In a two-temperature refrigeration system

5 the combination of a low temperature evaporator in heat exchange relation to a compartment to be cooled, means forming a path for a heat exchange liquid through said evaporator but isolated from the refrigerant therein, a heat exchanger in thermal relation to a second compartment to be cooled to a higher temperature, a secondary fluid circuit comprising the heat exchanger, said means, and connecting conduits, 10 means responsive to temperatures at the evaporator and at the heat exchanger for regulating flow in the secondary circuit, one of said connecting conduits being provided with two branches, a second heat exchanger removably connected to said branches, and a tertiary circuit including the second heat exchanger and said branches adapted to receive temporary shunted flow of the heat exchange liquid from the secondary circuit at controlled intervals.

15 20 9. In a two-temperature refrigeration system the combination of a low temperature evaporator in heat exchange relation to a compartment to be cooled, means forming a path for a heat exchange liquid through said evaporator but isolated from the refrigerant therein, a heat exchanger in thermal relation to a second compartment to be cooled to a higher temperature, a secondary fluid circuit comprising the heat exchanger, said means, and connecting conduits, 25 30 means responsive to temperatures at the evaporator and at the heat exchanger for regulating flow in the secondary circuit, and a tertiary heat exchange circuit paralleling said second circuit at one portion thereof removably associated with said heat exchanger, said tertiary circuit comprising means for detachably connecting fluid passages in the tertiary circuit with the fluid passages of the secondary circuit to receive temporary shunted flow from said second circuit.
